UNITED STATES PATENT OFFICE

KATHERINE E. UHRIG AND ANNA K. UHRIG, OF DAYTON, OHIO

DESIGN FOR AN ARM SLING

Application filed July 8, 1932. Serial No. 44,287. Term of patent 7 years.

To all whom it may concern:

Be it known that we, KATHERINE E. UHRIG and ANNA K. UHRIG, citizens of the United States, residing at Dayton, in the county of Montgomery and State of Ohio, have invented a new, original, and ornamental Design for Arm Slings, of which the following is a specification, reference being had to the accompanying drawing, forming part thereof, in which—

Fig. 1 is a front perspective view of the

arm sling in the position it assumes when in use.

Fig. 2 is a rear perspective view of the arm sling in the position it assumes when in use.

We claim:

The ornamental design for an arm sling, as shown.

In testimony whereof we affix our signatures.

KATHERINE E. UHRIG.
ANNA K. UHRIG.
